UNITED STATES PATENT OFFICE.

JOHN F. KELLY, OF TRENTON, NEW JERSEY, ASSIGNOR TO THOMAS MADDOCK'S SONS COMPANY, A CORPORATION OF NEW JERSEY.

LAVATORY-BASIN.

SPECIFICATION forming part of Letters Patent No. 756,239, dated April 5, 1904.

Application filed January 4, 1904. Serial No. 187,692. (No model.)

To all whom it may concern:

Be it known that I, JOHN F. KELLY, a citizen of the United States, residing at Trenton, county of Mercer, State of New Jersey, have 5 invented certain new and useful Improvements in Lavatory-Basins; and I do hereby declare the following to be a full, clear, and exact description of the invention, such as will enable others skilled in the art to which it appertains 10 to make and use the same.

The invention relates to lavatory-basins that are made out of porcelain, clay, or other plastic material. As now constructed these basins comprise a bowl and an outlying ledge or 15 table-like slab, which surrounds the bowl and extends horizontally outward at varying distances from the bowl. The slab is integral with the bowl, and the basin is formed complete when the material of which it is composed is in a plastic state. It is then put in 20 the usual saggar and baked or burned in a kiln to harden it, after which it is glazed and again fired in the furnace to set the glaze and give the basin the customary enamel finish. 25 In the manufacture of these basins considerable difficulty has been encountered in preventing the slabs from warping, and they have been provided with curtains or flanges running around their edges for the twofold purpose of stiffening the slabs to prevent them 30 from warping during the baking process and to give the completed basin a more substantial and artistic finish. These flanges need to be supported while the basin is in its plastic state and during the process of baking, and it 35 has been proposed to extend them inward and connect them to the outer side of the bowl; but this connection to the bowl is objectionable, for the reason that the material of which 40 the basin is composed shrinks considerably in the process of baking and the connection frequently pulls away from the bowl or cracks the bowl, particularly at those parts of the basin where the flange is farthest from the bowl and 45 the connection is consequently longest.

The object of the present invention is to avoid the above-explained difficulties without departing from the accepted type of basin having the depending flange around the edge

of the slab and without depriving the flange 50 of the support which is necessary to sustain it in the process of baking and prevent the warping of the slab.

To this end the invention consists generally in connecting or uniting the flange to the under side of the slab outside of the circumference of the bowl instead of connecting it to the bowl itself.

In the accompanying drawings a well-known form of basin is illustrated having the invention applied thereto.

In the drawings, Figure 1 is a plan view of the under side of the basin. Fig. 2 is a vertical section taken across the basin through the center of the bowl, and Fig. 3 is a sectional view showing in detail the manner of fastening the legs to the basin.

Referring to the views, *a* denotes the bowl, *b* the ledge or slab, and *c* the marginal flange or curtain extending around the slab and depending from its edge. The shape of the flange is unimportant, and it may extend straight down, as shown, at the back of the basin or downwardly and inwardly, as indicated, at the front of the basin.

As best shown in Fig. 1, the basin is usually of a generally rectangular outline; but the bowl is preferably oval or circular. Consequently the width of the slab between the bowl and the flange varies considerably, being 75 widest at the back side of the basin and diminishing to its narrowest point at the front side thereof. The connection between the flange and the slab is shown at *d*. In the completed basin it is, in effect, a continuation of 80 the flange, as shown in Fig. 2. In the process of manufacture, however, it is preferably a separate web of plastic material, which is united to the lower end of the flange; but whether made separate from the flange or by 85 continuing the lower edge of the flange and turning it upward the invention is the same. Fig. 1 best illustrates the line where this connection is united to the slab. It extends upward from the lower edge of the flange, as 90 shown in Fig. 2, and is united to the under side of the slab, leaving the bowl free and without attachments to its surface. The con-

95

nection need not extend from the extreme edge of the flange, but may be united thereto at any point, nor need the union between this connection and the under side of the slab be continuous all the way around. The advantages of the invention are best realized by keeping the connection free of the bowl at all points; but I should not regard it as a departure from the invention if in addition to 10 the arrangement above suggested the connection *d* should be united to the bowl at the point where the shrinkage of the material during baking would be the least liable to fracture the union, which of course would be at 15 the point where the union was shortest.

In Fig. 1 the letters *h* denote openings that are formed at the corners of the basin in the horizontal part of the connection *d*. They are oblong and are preferably of the shape shown 20 in the figure and serve the double function of permitting the escape of air from the space *i*, formed by the flange *c* and the connection *d*, during the process of baking and providing means for attaching the legs which support 25 the basin. These legs are attached, as shown in Fig. 3, where *e* denotes a bolt having an oblong head corresponding in shape to the openings *h* and having a threaded lower end. The head of the bolt is passed through 30 the opening and turned half-way around, so that it cannot be withdrawn. A washer *f* is then screwed or slipped onto the end of the bolt tightly against the under side of the connection, and the leg *g* is screwed up against 35 the nut, jamming it against the connection. This closes the opening completely and secures the leg firmly in place without leaving any parts exposed and without the necessity of forming additional openings in the connection *d* for 40 manipulating the fastenings. The construction being as thus described, it is to be noted that there are no recesses or partly-inclosed spaces underneath or on any part of the basin where dust, dirt, or vermin could collect, the 45 closure of the openings *h* by the leg-fastenings above described making the inclosed space *i* perfectly tight all around the basin. Apart from the advantage of venting this space during the baking operation this is an im- 50 portant sanitary feature of the completed basin when set up.

Having thus described my invention, what I claim is—

1. In a porcelain or like lavatory-basin that is formed complete of plastic material and afterward baked or fired, the combination of 55 a bowl, an integral ledge or table-like slab projecting outward from the upper edge of the bowl, a flange or curtain extending around and depending from the edge of the slab, and 60 a connection extending inward from the flange and united to the slab outside of the circumference of the bowl.

2. In a porcelain or like lavatory-basin that is formed complete of plastic material and 65 afterward baked or fired, the combination of a bowl, an integral ledge or table-like slab projecting outward from the upper edge of the bowl, and a flange or curtain running 70 around and depending from the edge of the slab, said flange being extended inward and united to the under side of the slab outside of the circumference of the bowl.

3. In a porcelain or like lavatory-basin, the combination of a bowl, a ledge or table-like 75 slab projecting outward therefrom, a flange or curtain extending around and depending from the slab, a connection extending inward from the flange and united to the slab outside of the circumference of the bowl, an oblong 80 opening in said connection, a bolt with an oblong head passed through said connection, and a supporting-leg for the basin screwed on the bolt.

4. In a porcelain or like lavatory-basin that 85 is formed complete of plastic material and afterward baked or fired, the combination of a bowl, an integral ledge or table-like slab projecting outward from the upper edge of the bowl, a flange or curtain extending around 90 and depending from the edge of the slab, a connection extending inward from the flange and united to the slab outside of the circumference of the bowl forming an inclosed space *i*, and an orifice *h* in the connection forming 95 a vent to the space *i* during the baking.

In testimony whereof I affix my signature in presence of two witnesses.

JOHN F. KELLY.
